KNIFE BLADE CLEANER

Harry Rietveld, Milwaukee, Wis.

Application October 15, 1937, Serial No. 169,213

4 Claims. (Cl. 15—236)

This invention appertains to cutlery, and more particularly to a novel attachment for a cake or similar knife.

One of the primary objects of my invention 5 is to provide a device which can be readily slipped on the blade of a knife and reciprocated longitudinally thereof for effectively clearing the blade of crumbs and the like adhering thereto after the slicing of cakes or other confections or 10 pastries.

Another salient object of my invention is to provide an attachment for knives embodying a pair of resilient wings for frictionally engaging the opposite sides of the blade, whereby when 15 the attachment is slid longitudinally of the blade, the same will be effectively cleaned for instant re-use.

A further important object of my invention is to provide a knife blade cleaner formed from 20 a single blank of material, and embodying a top guide plate for engaging the upper edge of the knife blade, and resilient side wings for engaging the opposite faces of the blade, the attachment being adapted to snugly engage the forward 25 end of the handle when the same is not in use.

A still further object of my invention is to provide a knife blade cleaner of the above character, which will be durable and efficient in use, one that will be simple and easy to manufacture, 30 and one which can be placed upon the market at a reasonable cost.

With these and other objects in view, the invention consists in the novel construction, arrangement, and formation of parts, as will be 35 hereinafter more specifically described, claimed, and illustrated in the accompanying drawing, in which drawing:

Figure 1 is a side elevation of my improved attachment, showing the same applied to a knife.

40 Figure 2 is a top plan view of the attachment, showing the same applied to a knife and illustrating the manner of using the same.

Figure 3 is a front elevation of the attachment, showing the same applied to a knife blade, 45 the blade being shown in section.

Figure 4 is an enlarged fragmentary section through the attachment, taken on the line 4—4 of Figure 3, looking in the direction of the arrows.

50 Referring to the drawing in detail, wherein similar reference characters designate corresponding parts throughout the several views, the letter A generally indicates my improved cleaning attachment for a knife K. The knife 55 K forms no part of my present invention and

has been illustrated merely to show the method of using the attachment.

The knife K embodies the usual knife blade 5 and manipulating handle 6. The attachment A comprises a body formed from a single blank 5 of sheet metal, and this body includes spaced, substantially parallel side walls 7, and a connecting top wall 8. The side and top walls have formed thereon an outside peripheral reinforcing flange 9. This flange has formed thereon laterally extending ears 10. If desired, these ears can be of an enlarged character to form manipulating finger pieces. However, I prefer to mould on the ear handles 11. The handles 11 are preferably formed from Celluloid, or other 15 composition, and the ears 10 are provided to permit the firm anchoring of the handles thereto.

Extending inwardly and forwardly from the side walls 7 are resilient cleaning wings 12. 20 These wings terminate in bent-out, sharpened cleaning edges 13, and these edges normally engage one another through the inherent resiliency of the wings 12. The top wall 8 also has formed thereon a forwardly extending guide lip 14.

As clearly shown in Figures 1 and 3, the lower 25 forward edges of the wings 12 are diverged outwardly and forwardly, as at 15, so as to facilitate the placing of the attachment on a knife blade.

The knife is held in the hand, and the attachment is placed on the upper edge thereof, with the portions 15 on either side thereof. By placing the thumb on the top wall 8, the attachment can be readily forced upon the blade 35 until the top wall and the lip engage the upper edge of the blade. The wings 12 will be forced apart by the blade, and the sharpened cleaning edges will engage the opposite faces of the blade.

Normally, the attachment A is slid back on 40 the blade until the same rests over the handle, as shown in dotted lines in Figure 1. After a slice of cake has been cut, the finger-pieces of the attachment are grasped, and the device is slid forwardly. The sharpened edges 13 will 45 then clean the blade of all crumbs, and the like. After the blade is cleaned, the attachment A is again slid back in place over the handle, and the knife may again be instantly used for cutting another piece of cake.

If the knife blade is utilized for serving the cake, the attachment may also be used for sliding the cake off the blade by moving the attachment forwardly into engagement with the cake.

Changes in details may be made without de- 50 55

parting from the spirit or the scope of this invention, but what I claim as new is:

1. An attachment for cleaning knife blades comprising a body including spaced parallel side walls, a connecting top wall, the body being adapted to straddle a knife blade, and forwardly and inwardly extending resilient wings, said wings having cleaning edges normally urged toward one another and into intimate contact simultaneously with the opposite faces of the knife blade by the inherent resiliency of said wings.
2. An attachment for cleaning knife blades comprising a body including spaced parallel side walls, a connecting top wall, forwardly and inwardly extending resilient wings, the body being adapted to straddle a knife blade, said wings having cleaning edges normally urged toward one another and into contact simultaneously with the opposite faces of the knife blade by the inherent resiliency of said wings, and outwardly flaring guiding lips formed on the forward lower corners of said wings.

3. An attachment for cleaning knife blades comprising a body including spaced side walls and a connecting top wall, said body being adapted to straddle a knife blade, forwardly and inwardly extending resilient wings on the side walls, said wings having cleaning edges for simultaneously engaging the opposite faces of the knife blade, and outwardly extending handles on the side walls.

4. An attachment for cleaning knife blades comprising a body including a pair of spaced side walls and a connecting top wall, the body being adapted to straddle a knife blade, an outwardly extending reinforcing flange on the side and top walls, inwardly projecting resilient cleaning wings on the side walls for simultaneously engaging the opposite faces of the knife blade, outwardly diverging guide lips on the lower forward corners of the wings, outwardly projecting ears on the flange on said side walls, and handles secured to said ears.

HARRY RIETVELD.
